UNITED STATES PATENT OFFICE.

HARVEY B. HITESHEW, OF PITTSBURG, PENNSYLVANIA.

HORIZONTALLY-PIVOTED WINDOW.

SPECIFICATION forming part of Letters Patent No. 787,378, dated April 18, 1905.

Application filed June 28, 1904. Serial No. 214,454.

To all whom it may concern:

Be it known that I, HARVEY B. HITESHEW, a citizen of the United States, residing at Pittsburgh, in the county of Allegheny and State of Pennsylvania, have invented a new and useful Improvement in Horizontally-Pivoted Windows, of which the following is a specification.

The invention relates to windows having the sash horizontally pivoted to strips on each side, which strips are adapted to be separated laterally from the sash and to travel longitudinally in the grooves of the window-frame; and the object of the improvement is to provide a pivotal connection which will permit a free lateral movement of the strips, with a tapered journal which can be tightened by endwise movement in a similar bearing to retard the rotation of the sash, by means of which the sash can be held in any position of rotation. This object is attained by the construction, mechanism, and arrangement illustrated in the accompanying drawings, in which—

Figure 1 is a fragmentary side view of a window frame and sash, showing the pivotal connection in longitudinal section; Fig. 2, an enlarged cross-section of the frame and sash on line 2 2, Fig. 1; Fig. 3, an enlarged longitudinal section of the pivot parts in the strip with the sash rotated to show a cross-section of the pivot parts therein; Fig. 4, a detached perspective view of the sash-plate; Fig. 5, a detached perspective view of the strip-plate; Fig. 6, a detached perspective view of the pivot with the key-pin opposite its aperture, and Fig. 7 a detached perspective view of the spiral spring and washer in relative position for assembling.

Similar numerals refer to similar parts throughout the drawings.

The window-frame 1 is made in the usual manner with a groove 2 on each side for receiving the respective sash-strips. The sash 3 is made less in width than the inside clear width of the frame, and the usual strips 4 are pivoted on the side edges of the sash and are adapted to operate in the respective frame-grooves. The adjoining faces of the sash edge and side strip are provided with the ridges 5 and 6, having inclined sides and arranged so that when the sash and strip are

aligned and brought together the ridges of the one will enter and fit in the grooves between the ridges of the other, as shown particularly in Fig. 2, and when the sash is rotated on the strips the ridges are forced out of the grooves 55 and bear against the crests of the opposing ridges, thus separating the strips from the sash according to the depth of the ridges, as shown in Fig. 3. To meet these conditions, the pivotal connection must provide for the 60 lateral movement of the strips as well as for the rotation of the sash. Each pivotal connection is composed of the sash-plate 7, the strip-plate 8, the pivot 9, the key-pin 10, the spiral spring 11, and the washer 12 and is 65 preferably located in the transverse axis of the sash. The sash-plate 7 is countersunk in the side edge of the sash, where it is attached, as by the screws 13. The face of the sash-plate is ridged like the edge of the sash, and 70 in the plate is provided the axial aperture 14, the inner part 15 of which has an angular cross-section. The strip-plate 8 is counter-sunk, preferably in the sash side of the strip, where it is attached, as by the screws 16, and 75 when so located is provided with the hub 17, which extends into the body of the strip. The pivot-bearing 18 is formed in the hub and is tapered from an enlarged aperture at the inner end to a slightly smaller aperture 80 at the face of the plate, and the face of the plate is ridged like the side of the strip. The pivot 9 is provided with the head 19 on one end, which is tapered like the bearing 18, in which it is adapted to rotate and to move 85 endwise therein as far as its tapered shape will permit, and with the angular inner end 20 similar in cross-section to the inner end of the axial aperture 14, in which it is adapted to operate endwise, but not to rotate. When 90 these parts are assembled, the spiral spring 11 and the washer 12 are respectively placed around the inner end of the pivot against the inner side of the sash-plate, where they are held by the key-pin 10, which is inserted in 95 the transverse aperture 21 near the inner end of the pivot. The parts are so proportioned that the spiral spring is compressed between the sash-plate and the washer and key-pin, by means of which the strip and sash are 100

pressed together between the pivot-head on the one end and the spiral spring on the other end of the pivot, and the strip is adapted to be separated from the sash by an endwise movement of the pivot in the axial aperture of the sash-plate and by a further compression of the spiral spring, which separation is necessary when the sash is rotated on the strips. The action of the spring always tends to draw the tapered pivot-head as a wedge into the similarly-tapered pivot-bearing, so that no looseness is ever possible in the pivotal connection. This wedge effect increases the friction of the pivot against the bearing and acts to retard its rotation therein. The normal energy of the spring is adjusted so that this retardation does not affect the free rotation of the pivot when the strips are alined with and closed against the edges of the sash; but when the strips are separated from the sash by the rotation of the latter the endwise movement of the pivot in the sash causes such a further compression of the spring that its increased action draws the tapered pivot-head into the similarly-tapered bearing so tightly that the rotation of the pivot is retarded to the extent of holding it in a given place as against a very positive force or pressure applied to rotate it.

30 What I claim as my invention, and desire to secure by Letters Patent, is—

1. A window-sash and a separable strip on its side edge, there being corresponding grooves and ridges on the adjoining faces, and a pivotal connection between the sash and the strip comprising a pivot having an endwise-movable non-rotatable bearing in the one and

a rotatable tapered bearing in the other, and a spring acting to draw the sash and the strip together and to draw the pivot into the tapered bearing. 4c

2. A pivotal connection for a window-sash and a separable strip comprising a pivot having an endwise-movable non-rotatable bearing in the one and a rotatable tapered bearing 41 in the other, and a spring acting to draw the sash and the strip together and to draw the pivot into the tapered bearing.

3. A pivotal connection for a window-sash and a separable strip comprising plates having an axial aperture in the one and a tapered bearing in the other, a non-rotatable endwise-movable pivot in the aperture having an inwardly-tapered head in the bearing, and means for drawing the head into the bearing. 5

4. In a pivotal connection for a window-sash and a separable strip, a pivot having an endwise-movable non-rotatable bearing in the one and a rotatable tapered bearing in the other, and a spring acting to draw the pivot into the 6 tapered bearing.

5. In a pivotal connection for a window-sash and a separable strip, a pivot having an endwise-movable non-rotatable bearing in the one and a rotatable tapered bearing in the other, 6 and means for moving the pivot into the tapered bearing.

In testimony whereof I have hereunto signed my name to this specification in the presence of two subscribing witnesses.

HARVEY B. HITESHEW.
